ELECTROMAGNETIC AUDIBLE-SIGNAL
DEVICE

Arthur B. Poole, Harwinton, Conn.

Application September 27, 1945, Serial No. 618,866

4 Claims. (Cl. 172—126)

1

The present invention relates to improvements in electromagnetic audible-signal devices and relates more particularly to devices of the character referred to which are especially suitable for use in electric clocks.

One of the objects of the present invention is to provide a superior electromagnetic audible-signal device having a compact and low-cost construction and arrangement of parts.

Another object of the present invention is to provide an audible-signal device of the character referred to comprising an electromagnet and a cooperating armature and in which the magnetic flux of the said electromagnet acts to cushion the movement of the said armature, in addition to attracting the same.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in front elevation of one form of electromagnetic audible-signal device embodying the present invention;

Fig. 2 is a sectional view thereof taken on the line 2—2 of Fig. 3, but on the same scale as Fig. 1;

Fig. 3 is a sectional view taken on the line 3—3 of Fig. 1 but on a larger scale;

Fig. 4 is a perspective view of the electromagnet-unit, detached; and

Fig. 5 is a perspective view of the armature, detached.

The particular embodiment of the present invention shown in the accompanying drawings and chosen for purposes of making clear the principles of the present invention, includes an electromagnet comprising a cup-shaped shell 10 which includes a cylindrically-contoured lateral wall 11 and an end wall 12 integral with the said lateral wall.

Integral with and projecting forwardly from the lateral wall 11 of the shell 10 are two pole-salients 13 and 14 located diametrically opposite each other and respectively adapted to project forwardly through arcuate slots 15 and 16, which latter extend from front to rear through a mounting-plate 17.

Located within the shell 10 is a spool 19 upon which is wound an energizing-coil 20. Extending axially through the spool 19 and hence also pass-

2

ing axially through the energizing-coil 20 and shell 10, is a core 21 having its forward end extended through a circular clearance-opening 22 formed in the mounting-plate 17 at a point midway between the arcuate slots 15 and 16 therein.

Rigidly secured to the forward portion of the core 21 is a plate-like flux-shunting member 23 adapted to shunt magnetic flux between the pole-salients 13 and 14 of the shell 10 and the said core 21. The said flux-shunting plate is not necessarily claimed herein but is included in the subject matter of my copending application filed on even date herewith and now issued as Patent No. 2,442,016.

Forwardly of the flux-shunting member 23, the core 21 is formed with a relatively-slender neck 24 terminating in a disk-like head 25. The said head normally projects part way into an aperture 26 formed centrally in a plate-like armature 27, as is especially well shown in Fig. 5.

The armature 27 above referred to is so sized as to freely fit in the space between the pole-salients 13 and 14 of the shell 10 and is secured in rearwardly-spaced relationship to a spring-like armature-arm 28 by means of studs 29—29. The upper end of the armature-arm 28 is secured in forwardly-spaced relationship with respect to the mounting-plate 17 by means of a stud 30, as is especially well shown in Fig. 3.

The parts 10, 21, 23 and 27 are formed of soft iron or other suitable magnetic material, while the parts 17, 28, 29 and 30 are preferably formed of non-magnetic material.

To provide for the turning of the flux-shunting member 23 above referred to, for purposes of shunting more or less of the magnetic flux between the pole-salients 13 and 14 on the one hand and the core 21 on the other hand, the said core is preferably mounted within the spool 19 with freedom for rotation therein. The rear face of the said flux-shunting member 23 is held in frictional engagement with the forward face of the mounting-plate 17 by means of a concavo-convex spring-washer 31.

The spring-washer 31 above referred to, has its outer edge pressing against the rear face of the end wall 12 of the shell 10 and has its central portion seated against the under face of the head of a retaining-screw 32 tightly threaded into the rear end of the core 21 so as to effectively become a part thereof for normal operating purposes.

In addition to serving to hold the flux-shunting member 23 in engagement with the forward face of the mounting-plate 17, the spring-washer 31 and the retaining-screw 32 also serve to hold

the respective forward faces of the shell 10 and the spool 19 against the rear face of the mounting-plate 17.

The energizing-coil 20 may be supplied with alternating current from any suitable source such, for instance, as a source of 60-cycle 110-volt current, or the said energizing-coil may be supplied with interrupted direct current in any suitable manner such, for instance, as in the manner common in the art of bells and buzzers.

Preferably and as shown, the lower end of the flexible armature-arm 28 is provided with a striker 33 which is adapted to strike any suitable object such, for instance, as a bell or gong.

The energization of the energizing-coil 20 will cause the pole-salients 13 and 14 of the shell 10 to assume one polarity at a given instant, while the head 25 of the core 21 assumes an opposite polarity. The magnetic flux thus produced will flow through the armature 27 and will attract the same against the tension of the resilient armature-arm 28 and will cause the striker 33 to strike any suitable object to produce the desired sound.

As the armature 27 is pulled inwardly as above described, it will move into a position slightly past a position wherein its front face becomes substantially flush with the respective outer faces of the pole-salients 13 and 14 and the head 25. The tendency of the armature 27 to continue its movement inwardly under the impetus imparted to it by the magnetic flux will be checked by the said magnetic flux without requiring a positive mechanical stop with its consequent noise which might interfere with the clarity of the desired signal and possibly cause ultimate damage to a clock mechanism.

As explained in my copending application previously identified, should the movement of the armature 27 be too violent or not sufficiently violent to meet the exigencies of a given situation, the flux-shunting member 23 may be turned by rotating the retaining-screw 32, to thus cause the said member to shunt more or less of the magnetic flux between the pole-salients 13 and 14 on the one hand and the core 21 on the other hand, thereby varying the amount of flux which will flow through the armature 27.

By aperturing the armature 27 or its equivalent, and utilizing the magnetic flux not only to move the said armature but to check the movement thereof, a highly efficient audible-signal device is provided which does not have its intended clarity of signals interfered with by objectionable noises made by efforts to mechanically check the movement of the armature.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An electromagnetic audible-signal device, including in combination: an energizing-coil; a magnetic core extending through the interior of the said energizing-coil and having a pole-salient adjacent one end projecting beyond the adjacent end of the said energizing-coil a distance materially greater than the thickness of the herein-after-mentioned armature; a magnetic shell extending over the exterior of the said energizing-

coil and provided at its end adjacent the pole-salient of the said core with two pole-salients located substantially diametrically opposite each other on the respective opposite sides of the pole-salient of the said core and projecting beyond the adjacent end of the said energizing-coil a distance materially greater than the thickness of the herein-after-mentioned armature; and an armature having a substantially-central opening therethrough adapted to freely fit over the pole-salient of the said core, and the said armature being shaped and sized to freely fit between the two said pole-salients of the said shell and to vibrate therebetween without striking any of the aforesaid pole-salients or the said energizing-coil.

2. An electromagnetic audible-signal device, including in combination: an energizing-coil; a magnetic core extending through the interior of the said energizing-coil and having a relatively-slender neck adjacent one end and an overhanging head at the end of the said neck projecting beyond the adjacent end of the said energizing-coil a distance materially greater than the thickness of the herein-after-mentioned armature; a magnetic shell extending over the exterior of the said energizing-coil and provided at its end adjacent the head of the said core with a pole-salient projecting beyond the adjacent end of the said energizing-coil a distance materially greater than the thickness of the herein-after-mentioned armature; and an armature having an opening therethrough adapted to freely fit over the head of the said core and the said armature being shaped and sized to freely fit between the head of the said core and the pole-salient of the said shell and to vibrate therebetween without striking any of the aforesaid pole-salients or the said energizing-coil.

3. An electromagnetic audible-signal device, including in combination: an energizing-coil; a magnetic core extending through the interior of the said energizing-coil and having a relatively-slender neck adjacent one end and an overhanging head at the end of the said neck projecting beyond the adjacent end of the said energizing-coil a distance materially greater than the thickness of the herein-after-mentioned armature; a magnetic shell extending over the exterior of the said energizing-coil and provided at its end adjacent the head of the said core with two pole-salients located substantially diametrically opposite each other on the respective opposite sides of the head of the said core and projecting beyond the adjacent end of the said energizing-coil a distance materially greater than the thickness of the herein-after-mentioned armature; and an armature having a substantially-central opening therethrough adapted to freely fit over the head of the said core and the said armature being shaped and sized to freely fit between the respective pole-salients of the said shell and to vibrate therebetween without striking any of the aforesaid pole-salients or the said energizing-coil.

4. An electromagnetic audible-signal device, including in combination: an energizing-coil; a magnetic core extending through the interior of the said energizing-coil and having a pole-salient adjacent one end projecting beyond the adjacent end of the said energizing-coil a distance materially greater than the thickness of the herein-after-mentioned armature; a magnetic shell extending over the exterior of the said energizing-coil and provided at its end adjacent the pole-salient of the said core with a pole-salient pro-

jecting beyond the adjacent end of the said energizing-coil a distance materially greater than the thickness of the hereinafter-mentioned armature; and an armature having a portion shaped and sized to freely fit between the respective pole-salients of the said core and of the said shell for movement between the same in a direction substantially parallel with the axis of the said core without striking either of the two said pole-salients or the said energizing-coil.
